UNITED STATES PATENT OFFICE.

GEORGE E. NERNEY, OF ATTLEBORO, MASSACHUSETTS.

DESIGN FOR A FRATERNAL EMBLEM.

41,063.

Specification for Design.

Patented Jan. 3, 1911.

Application filed November 5, 1910. Serial No. 590,904. Term of patent 7 years.

To all whom it may concern:

Be it known that I, GEORGE E. NERNEY, a citizen of the United States, residing at Attleboro, in the county of Bristol and State of Massachusetts, have invented a new, original, and ornamental Design for a Fraternal Emblem, of which the following is a specification, reference being had to the accompanying drawing, forming part thereof.

The figure is a plan view of a fraternal

emblem, showing my new design, for use as a button, charm, pin, and for ornamental jewelry.

I claim:

The ornamental design for a fraternal emblem, as shown.

GEORGE E. NERNEY.
